LOOSE-LEAF DEVICE

Abraham M. Rabinof, New Rochelle, N. Y.

Application January 6, 1936, Serial No. 57,793

5 Claims. (Cl. 129—24)

This invention relates to loose-leaf devices, particularly those having embodied therein a set of split rings adapted to be opened and closed by manual manipulation.

5 In most loose-leaf books of this character, the rings are brought into their open positions by manually spreading them apart; and in other devices of this nature, the opening operation is effected by the use of flat press-board inserts suspended from the rings and flanking the loose-leaf pages, or by applying manual pressure to an element contained within the covers of the book. In some instances, where pressure can be applied to an outside portion of the book to cause an opening of the rings, a relatively expensive structure is necessary. It is hence within the contemplation of this invention to improve upon existing devices in this category by presenting a novel structure of simple and inexpensive design,—one which will eliminate the cost and operating disadvantages of other loose-leaf devices, and which will particularly facilitate the opening and closing of the rings.

Another object of this invention is to enable 25 a loose-leaf device to be readily operated upon instant inspection, by rendering visible the precise portion of the book which is to be manually manipulated from the outside by simple finger pressure.

30 Still another object of this invention is to permit of the easy and ready assembly of the parts comprising the structure, and to enable certain elements thereof to be readily applied to existing devices to effectuate the results contemplated by my invention.

Other objects, features and advantages will appear from the drawing and the description hereinafter given.

40 Referring to the drawing,

Figure 1 is a rear view of a closed loose-leaf book containing one form of my invention wherein an exposed button is adapted for manual pressure to open the series of split rings.

45 Figure 2 is a vertical section of Figure 1 taken through line 2—2.

Figure 3 is a transverse section of Figure 2 taken along line 3—3.

50 Figure 4 is an enlarged fragmentary end view of the device of Figures 1 and 2.

Figure 5 is an enlarged fragmentary vertical section of Figure 2 taken along line 5—5.

55 Figure 6 is an enlarged fragmentary end section showing the position of the parts when the

book is opened after the application of pressure upon the exposed button.

In the drawing, the book consists of the covers 12 and 13 joined by the flexible middle portion 14. The channel-like housing 15 is open at the top, the said middle portion 14 forming a cover therefor. The housing is provided at its ends with flaps 16 and 17 which are bent over upon themselves to clamp therebetween the lateral edges of the said middle portion 14. The split rings 18 and 19 extend through the resilient base 20 of the housing and are joined to the two substantially parallel coacting elements 21 and 22 extending lengthwise of the housing,—the sections 23 of the rings being connected to the element 21, and the sections 24 to the element 22. The said coacting elements 21 and 22 have abutting edges 25 and 26 which are in constant engagement and movable to an upper level where the rings are closed, as shown in Figure 5, and to a lower level where the rings are open, as shown in Figure 6, by means of toggle action and the resilient base 20.

Cognizance is taken of the fact that a portion of the loose-leaf device above described is, in principle at least, frequently employed in various structures. It is my purpose, in setting forth the novelty of my invention, as disclosed in the various forms thereof, to apply manual pressure from the outside of such a structure upon the middle portion of the book, such as 14 above referred to,—this pressure to be applied at a predetermined point as indicated by a visible marker. My invention contemplates that this middle portion be flexible, so that the pressure applied thereupon can be transmitted to a depressing member or plate interposed between said middle portion and the parallel coacting elements such as 21 and 22 above referred to. This will cause a downward movement of the plate, and a consequent depression of the said abutting edges 25 and 26 from their upper or closed level to the lower level where the rings will be opened. Some of the forms of my invention which will accomplish this purpose will hereinafter be set forth.

Referring to Figure 2, it will be seen that the plate 27, consisting of a small flat section of metal, is interposed between the middle portion 14 and the coacting elements 21 and 22. This plate is attached to or suspended from the shank of a rivet or button 28, which extends through an opening in the portion 14 and is suitably at-

tached thereto,—the top or head of the button being visibly exposed.

In the operation of the above-described form of my invention, downward manual pressure is applied upon the button 28, which will cause the middle portion 14 to flex downwardly to force the plate 27 against the elements 21 and 22. The resulting pressure forces the abutting edges 25 and 26 of these elements downwardly to their lower projected level to cause a spreading apart of the sections 23 and 24 of the split rings 18 and 19, into their open positions. It will thus readily be seen that it is the flexibility of the portion 14 which permits a proper functioning of this device, and that the suspension of the button and attached plate 27 from portion 14 obviates the use of an underlying supporting member such as the usual stiffener employed in loose-leaf binders. The housing 15 is completely enclosed except for the top opening, and the closure therefor is the above-referred-to flexible middle portion 14. And inasmuch as the button 28 is exposed to view, it serves as a visible marker upon which pressure can be applied at the proper point. If the surface of this button contains a notation, such as the words "press down", any person will be able to operate this device upon first inspection. Such an arrangement has the obvious advantage of eliminating guess work in locating the point of manual manipulation, and is effective in enabling pressure to be applied to that portion of the device which will cause a most efficient operation thereof,—that is, a quick opening with the least amount of effort.

The employment of the flaps 16 and 17, preferably as an integral part of the housing, further simplifies the construction, inasmuch as the terminal portions of these flaps are bent back upon themselves to firmly clasp therebetween the lateral sides of the portion 14 without the use of any additional securing means,—thereby rendering the device easy to assemble and inexpensive to fabricate. Although the coacting elements 21 and 22 are shown to be longitudinally disposed wires forming continuous parts of the sections 23 and 24 of the rings, it is apparent that this invention is equally applicable to other analogous structures, such as those containing two parallel abutting plates extending lengthwise of the housing.

It will be noted that in the form of my invention hereinabove referred to, a depressing member or plate is interposed between the flexible middle portion of the book and longitudinally disposed coacting member associated with split rings, the said middle portion containing visible markers upon which pressure is applied to cause an opening of the rings. It will also be observed that there is a housing completely enclosed except for a top opening which is covered by the said middle portion,—said housing being channel-like in shape and containing lateral flaps the terminals of which serve as clamps for the middle portion.

It is of course understood that the various embodiments above described and shown in the drawing are illustrative of my invention and not employed by way of limitation, inasmuch as numerous changes and modifications may be made within the scope of the appended claims without departing from the spirit of this invention.

What I claim is:

1. In a loose-leaf book, a pair of covers joined by a flexible middle portion, a channel-like hous-

ing on the inner face of said middle portion and open at the side towards said face and having end flaps the terminals of which are in clamping engagement with the lateral sides of the middle portion, two coacting elements extending lengthwise within the housing and having abutting edges movable inwardly of the book, a split ring each section of which extends through the base of the housing and is operatively associated with said elements, depressing means secured to said flexible middle portion and positioned intermediate said middle portion and said coacting elements and engageable therewith to operatively depress said abutting edges inwardly of the book, and a visible marker carried by said middle portion and affixed to said depressing means and being adapted to receive manual pressure thereupon for flexing said middle portion inwardly and consequently forcing said depressing means into operative engagement with said coacting elements.

2. In a loose-leaf book, a pair of covers joined by a flexible middle portion, a channel-like housing on the inner face of said middle portion and open at the side towards said face and having end flaps the terminals of which are in clamping engagement with the lateral sides of the middle portion, two coacting elements extending lengthwise within the housing and having abutting edges movable inwardly of the book, a split ring each section of which extends through the base of the housing and is operatively associated with said elements, depressing means secured to said flexible middle portion and positioned intermediate said middle portion and said coacting elements and engageable therewith to operatively depress said abutting edges inwardly of the book, and an exposed button carried by said middle portion and extending through a hole therein, said button being attached to said depressing means and being adapted to receive manual pressure thereupon for flexing said middle portion inwardly and consequently forcing said depressing means into operative engagement with said coacting elements.

3. In a loose-leaf book, a pair of covers joined by a flexible middle portion, a channel-like housing on the inner face of said middle portion and open at the side towards said face and having end flaps the terminals of which are in clamping engagement with the lateral sides of the middle portion, two coacting elements extending lengthwise within the housing and having abutting edges movable inwardly of the book, a split ring each section of which extends through the base of the housing and is operatively associated with said elements, a substantially flat plate intermediate and contiguous to said flexible middle portion and said coacting elements and engageable therewith to depress said abutting edges inwardly of the book, and an exposed button carried by said middle portion and extending through a hole therein, said button having attached thereto the said plate.

4. In a loose-leaf book, a pair of covers joined by a flexible middle portion, a channel-like housing on the inner face of said middle portion and open at the side towards said face and having end flaps the terminals of which are in clamping engagement with the lateral sides of the middle portion, two coacting elements extending lengthwise within the housing and having abutting edges movable inwardly of the book, a split ring each section of which extends through the base of the housing and is operatively associated

with said elements, a substantially flat plate extending lengthwise within the housing and positioned intermediate said flexible middle portion and said coating elements and contiguous therewith, and a visible marker carried by said middle portion and attached to said plate and being adapted to receive manual pressure thereupon for flexing said middle portion inwardly to force said plate into operative engagement with the said coating elements.

5. In a loose-leaf book having a pair of covers joined by a flexible middle portion, a housing on

the innermost face of the middle portion and open at the side towards said face, separable split ring means extending through the base of the housing, depressing means secured to said flexible middle portion and operatively engageable with said split ring means for causing them to separate, and an exposed button attached to said depressing means and adapted to receive manual pressure thereupon for flexing said middle portion inwardly of the book and operatively actuating the depressing means.

10 ABRAHAM M. RABINOF.
